GEORGE W. CILLEY AND GEORGE H. SPAULDING, OF NORWICH, CONNECTICUT, ASSIGNEES
TO THE NORWICH PAPER-COLLAR COMPANY, OF THE SAME PLACE, ASSIGNEES TO
AMERICAN MOULDED-COLLAR COMPANY.

Letters Patent No. 73,693, dated January 28, 1868.

IMPROVEMENT IN MACHINE FOR MOULDING PAPER COLLARS.

The Schedule referred to in these Letters Patent and making part of the same.

TO ALL WHOM IT MAY CONCERN:

Be it known that we, GEORGE W. CILLEY and GEORGE H. SPAULDING, both of Norwich, in the county of New London, and State of Connecticut, have invented a new and improved Mode of Moulding Collars; and we do hereby declare that the following is a full, clear, and exact description of the same, reference being had to the accompanying drawings, making a portion of this specification, in which—

Figure 1 is a plan or top view of the apparatus employed in moulding and shaping collars according to our invention.

Figure 2 is a side view of the same.

Figure 3 is a vertical transverse section of the same, taken in the line $z z$ of fig. 2.

Figure 4 is a detached view of one portion of the same.

Similar letters of reference indicate corresponding parts in all the figures.

This invention relates more especially to the manufacture of paper collars, and it consists in moulding or shaping the collars between two flexible clamping-plates or holders, which clamp that portion of the collar which it is desired to mould, in such manner as to effectually shape such portion into the form required in the finished collar.

The invention further consists in two flexible clamping-plates or formers, in combination with suitable means for operating the same, whereby the collar, or such portion thereof as may be desirable, may be clamped between the said plates, and be made to assume the desired shape or configuration.

The invention further consists in a novel combination of parts, whereby not only may the moulding-apparatus be very conveniently manipulated when in use, but may, when desired, be securely attached to any suitable support.

To enable others to understand the construction and operation of our invention, we will proceed to describe it with reference to the drawings.

The two clamping-plates or formers A and B are made preferably of sheet steel, and are of any suitable width and length, and, when desired, may be slotted vertically at their upper edges, as shown at a , in figs. 1 and 2, in order to give some degree of vertical elasticity to the plates or formers. These two clamping-plates, at the central portion of their upper edges, are curved over, as shown more clearly at b , in figs. 1 and 3, in such manner and form that the transverse section of such portion of each plate will correspond to the transverse curvature of the back part of the finished collar, to which the said curved or bent-over portions of the plates are designed to give form and shape, as hereinafter presently set forth. That surface of the inner plate, A, toward the plate B, has attached to it a layer or thickness, c , of India rubber or equivalent elastic material, and, attached to the outermost side of this plate A, at each end thereof, is a vertical strap, d , of a hinge, the pivot e of which is shown in dotted lines in fig. 2, and the other strap, f , of which turns upon the, said pivot, and is brought upward upon the opposite or outer side of the other plate, B, as shown in fig. 1. Passing through slots formed in the two straps of each hinge, and in the ends of the plates A B, situated between the said straps, is a bar, g , in one end of which is fixed a transverse pin, a' , which prevents it from being drawn out of its place; and, in the opposite end of such bar, is pivoted a cam or eccentric, h , which is furnished with a handle, i , in such manner that, when the said handles are turned outward into the position shown in fig. 1, the ends of the plates A B will be tightly held or compressed between the two hinge-straps $d f$. Formed upon one of the plates A B, one at each end thereof, are two springs, m , which tend to press apart the said plates, when relieved from the action of the cams or eccentrics h , as presently herein explained. Secured centrally upon the outer side of the plate A is a strong supporting-piece, n , which, being attached, by screws or otherwise, to a bench or table, holds the apparatus in proper position when in use.

In the operation of moulding or shaping the collars, the handles i are first turned inward toward each other, so as to relieve the hinge-strap f from the action of the cams or eccentrics h , and thus enable the springs m to force the plates A B apart to a sufficient extent to permit the insertion between them of the "inner fold" of the collar, with the outer fold of such collar, in contact with the outer surface of the plate B, as shown in red

outline in fig. 3, which being done, the handles *i* are turned outward into the position shown in fig. 1, and thus compress together the ends of the plates A B, as hereinbefore explained. The ends of the plates or formers A B are then, by means of the handles *i*, bent inward, as indicated by the arrows in fig. 1, until the said plates assume the form of an arc of a circle, and, inasmuch as the inner plate A bends upon a smaller arc or circle than the other or outer plate B, it follows that the said plates, when thus bent, are forced toward each other with the greatest force at their central parts, or, in other words, at the curved or bent-over parts *b* thereof, and, consequently, that portion of the collar situated between such parts, *b*, will, be clamped with great tightness, and, consequently, moulded or pressed into a shape corresponding to the aforesaid parts *b*, such pressure at the same time preventing any stretching or distortion of the portion thus moulded or shaped, and the end portions of the collar being permitted to adapt themselves to the altered shape of the back or moulded portion (just described) thereof, by slipping slightly between the plates A B, such slipping being permitted by the comparatively moderate degree of pressure exerted upon such end portions of the collar, by the end portions between which they are clamped, of the plates or formers.

The operation of moulding or shaping the collar being thus completed, the plates A B are brought back to or allowed to resume their straight position, and the handles *i* being moved inward, as hereinbefore explained, the springs *m* move the plates or formers apart, and permit the removal of the moulded collar, and the insertion of another, which is then subjected to the moulding operation, in the same manner as hereinbefore set forth.

Instead of being made of sheet metal, as hereinbefore described, the clamping-plates or formers may be made of any other suitable material, and of any construction which will secure their flexibility in the moulding or shaping operation.

What we claim as our invention, and desire to secure by Letters Patent, is—

1. The two flexible clamping-plates or formers A B, in combination with eccentrics *h* and handles *i*, for closing and bending the same, substantially as and for the purpose specified.
2. The cams or eccentrics *h*, handles *i*, hinge-straps *f*, and bars *g*, in combination with the clamping-plates A B, springs *m*, and supporting-piece *n*, substantially as and for the purpose specified.

GEORGE W. CILLEY,
GEORGE H. SPAULDING.
